UNITED STATES PATENT OFFICE.

RICHARD ANTON NOWAK, OF PORTLAND, OREGON.

GARMENT FASTENER.

Application filed August 28, 1922. Serial No. 584,388.

To all whom it may concern:

Be it known that I, RICHARD ANTON NOWAK, a citizen of the United States, and a resident of Portland, county of Multnomah, State of Oregon, have invented a new and useful Garment Fastener, of which the following is a specification.

The present invention relates to improvements in garment fasteners and its particular object is to provide a device of the character described that will dispense with the buttons and buttonholes now commonly used for that purpose. A further object of the invention is to provide a fastener of this character that can be cheaply constructed and is easily operated.

With these objects in mind I have shown the preferred form of my invention in the accompanying drawing in which Figure 1 represents a perspective view of the two members of my fastener, Figure 2 a side elevation of the two members in their interlocked relation, partly shown in section, and Figure 3 a perspective view of one of the members disclosing additional features of the same. While I have shown only the preferred form of the invention, I wish to have it understood that various changes or modifications might be made within the scope of the claims hereto attached without departing from the spirit of the invention.

My garment fastener comprises two principal portions, the receiving member (1) and the engaging member (2). The former consists preferably of a strip of metal bent into U-shape, one of the legs (3) being provided with perforations (4), by means of which it may be secured to one edge of the garment (6) as shown at (7). The base portion (8) of the U-shaped member is provided with a slot (9) communicating with a recess (11) of smaller dimensions so as to form shoulders (12). The extreme end of the second leg (13) of the U-shaped member runs out into curved projections (14), curved inwardly for the purpose of protecting other garments lying underneath the garment to be fastened.

The engaging member (2) comprises a

flat strip of metal (16) perforated as shown at (17) and provided with a projection (18) bent upon itself as shown at (19) so as to form a substantially V-shaped spring. The extreme end (21) of the spring terminates in a perpendicular arm (22) which is narrower than the width of the spring so as to form the shoulders (23). The arm carries in its top end a button (24) which may be secured thereto in an artistic manner, as by the crown (26) shown in the drawing. The engaging member is secured to the other edge (27) of the garment as shown at (28).

The operation of the device will be readily understood by the foregoing description. To fasten the garment it is only necessary to introduce the V-shaped spring of the engaging member through the slot of the receiving member. During this process the spring is compressed until its extreme end has passed the slot when it will expand and the shoulders (23) of the spring engage the shoulders (12) of the recess (11). In this position the two members are interlocked and can be disengaged from one another only by depressing the upper leaf of the spring by means of the button (24) which allows the spring to be withdrawn through the slot (9).

I claim:

In a garment fastener a U-shaped receiving member having a slot in its base, a recess adjacent to the slot forming shoulders in the material and a plurality of perforations in one of its legs for receiving means for fastening the same to one edge of the garment, and an engaging member comprising a plate having perforations therein allowing the same to be fastened to the other edge of the garment and having a projection turned upon itself adapted to be forced through the slot terminating in a perpendicular arm forming shoulders with the same adapted to co-operate with the shoulders in the receiving member in locking the two members, the corners of the free leg of the receiving member being bent inwardly to prevent injury to adjacent garments.

RICHARD ANTON NOWAK.
